UNITED STATES PATENT OFFICE

FERDINAND PHILIPPE ANDRÉ ERNEST DELPECH, OF PARIS, FRANCE

TIME-RECORDING APPARATUS

Application filed November 9, 1926, Serial No. 147,273, and in France November 27, 1925.

This invention comprises improvements in time checking and recording apparatus and it relates to apparatus adapted for recording upon charts, cards or paper slips, hereinafter called slips, the attendances and hours of entering and leaving establishments such as offices, shops, and factories. Apparatus of this kind may also be used for recording the time spent upon a job, and for other purposes 10 where an accurate record of time spent is required.

One object of this invention is to provide an apparatus of the kind in question adapted for recording the instant of its operation in 15 an accurate and indelible manner and by a single operation, either upon one single slip or simultaneously upon several slips. The cards and the apparatus may be adapted for operation over weekly periods whereby the 20 regularity of attendance of members of a staff and the hours of entering and leaving premises during that week may be accurately and indelibly recorded.

A further object of the invention is to 25 provide a time recorder or check in which only a simple linear measure of time is involved in the calculation of the time periods elapsing between the start of a job and the finish, or between the moments of restarting 30 and suspending a work operation during a period of a number of days, as for example a week.

Yet another object is to provide a combination comprising a travelling punch, a clock 35 mechanism, a transmission operated by the clock imparting linear travel to the punch, whereby the travel of the latter is proportional to the time, and a releasable slip carrier adapted automatically to bring a contained slip on to the punch for the record 40 to be made.

A further object is to provide for periodic displacements of the line of travel of the punch whereby the path of travel during a 45 new period is displaced from the path followed during the preceding period. This displacement of the line of travel may be accomplished either automatically by the action of the clock movement or by hand adjustment.

Another object is to provide in the combination a slip carrier adapted, at the moment of its release, for striking the punch with a regulatable force sufficient for causing the perforation by the punch one or more 55 slips contained in such carrier.

Another object is to provide a slip holder for use in the carrier, the said holder being adapted for receiving and holding the slips with such accuracy that the proper disposition of the slips in the carrier is ensured without the need for the exercise of any particular skill or precaution. 60

The slips to be employed in the apparatus are provided with lines or divisions representative of time periods and corresponding with the path of travel of the punch. These lines or chartings may be adequate for one or several days and usually will be suitable for a period of one week. 65

The invention will be more fully described with reference to the annexed drawings forming part of this specification, in which drawings are illustrated suitable practical examples of construction. In the said drawings: 70

Figure 1 is a perspective view of one construction of apparatus, part of the casing and a portion of the dial plate being broken away to disclose parts beneath. 75

Figure 2 is a transverse section of an apparatus similar to that seen in Figure 1.

Figure 3 is a detail view of a modified mechanism for imparting travel to the punch. 80

Figure 4 is a face view of a slip suitable for use in the apparatus.

Figure 5 is a perspective view of a slip holder.

Figure 6 is a perspective view of one of the wings or sides of the slip holder. 90

Figure 7 is a sectional view of a traveller on which the punch is mounted directly.

Figure 8 is a view of a heart cam adapted for moving the traveller along its path. 95

In Figures 1 and 2, *a* is the clock mechanism, *b* is the casing and *c* is the dial plate supported above the clock by suitable pillars on the bottom of the casing. A heart cam 4 is fixed on the minute arbor of the clock. 100

The record slips, such as those seen in Figure 4, are receivable by a carrier *g* swingable about a horizontal axis *h* upon which is fixed externally of the casing an operating lever *j*.

5 The casing is of wood or any other suitable material and is provided in its top and front walls with rectangular glass panes. In the top there is an opening 20 through which the slips are inserted when the carrier *g* is in its 10 vertical position.

10 The slip carrier *g* comprises two plates separated by a space *u* into which is insertable a slip holder, hereinafter described with reference to Figures 5 and 6, the said slip 15 holder being adapted for enabling a very accurate disposition of the slips in the apparatus to be obtained without the exercise of any undue care or skill. The slip holder has two wings or sides 7 and 8 hinged together 20 at 9 and vertical edge portions of the wings 7 and 8 come accurately together when the holder is closed. The wing 7 has near its lower edge projections 10 whilst the wing 8 has perforations 11 corresponding with these 25 projections. The slip, see Figure 4, is formed with perforations 12 so disposed that when they are entered by the projections 10 which are of exactly the same diameter, the said slip is correctly disposed within the 30 holder. The wings of the holder are formed with projections 13 and 14 for bearing against the walls of the space *u* in the carrier for ensuring a correct positioning of the holder within the carrier. The projections 35 13 at one extremity are different from those at the opposite extremity as will be seen from Figure 5, the projections 14 being flanked on one side by flanges 24 the purpose of which will be explained.

40 The dial plate *c* is formed with a slot 2 in which slides a small traveller 3 carrying on top a punch 15, see also Figure 7. The traveller 3 is moved along the slot 2 with a uniform movement in such manner that its distance from the arbor of the clock at any moment is a measure of the time. For this purpose, the traveller is formed so as to cage a ball 16 at its lower end, as seen in Figure 7, and this ball rolls in a channel 17 formed 45 in the upper surface of a heart cam 4 seen separately in Figure 8. The two curves constituting this heart cam are fractions of spirals of Archimedean, curvature of which the equation is, as is known $\rho = k\omega$. The ball 50 16 is depressed by a spring 18 for maintaining engagement with the channel 17.

With a clock having a twelve hour circle, the traveller 3 advances towards the centre during six hours and recedes from the centre

60 during the following six hours and so on. The movement thus imparted to the punch 15 will be too slow for precise records by the punch unless the apparatus be given considerable dimensions. To avoid this inconvenience, an expedient is adopted whereby

the traveller has a speed which is double that of the traveller seen in Figure 1. In practice, the parts are set so that the punch moves in one direction from six o'clock to midday and in the opposite direction from midday to six o'clock p. m. or 18 o'clock with a 24 hour dial. For successive records during a day, the slips could be inserted facing the operator during the six hours that the traveller approaches the centre and could be inserted in the reverse position during the six hours that the traveller recedes from the centre. 70 75

75 Referring to Figure 1, it will be seen that the opening 20 has at its ends hinged shutters or flaps 21 and 22. These shutters are formed with notches 23 which are narrower than the slot opening 20. If the shutter 21 to the left is closed down, it is necessary to insert the holder, Figure 5, with the flanges 24 to the left so that they will enter the notch in the shutter 21. If the shutter 21 is raised and the shutter 22 is closed down, then the said holder must be inserted with the flanges 24 disposed at the right hand side 90 for entering the notch in the shutter 22. This arrangement avoids any possible error in the introduction of the slips in the appropriate manner. 95

95 For regulating the apparatus according to the day of the week, for example, it suffices to advance or recede to a given degree all the clockwork mechanism and the plate *c*. For this purpose, this mechanism is placed entirely upon a movable plate 25 which can slide in the guides 26 either by means of a control lever 27 or by any other appropriate known arrangement (for example an endless thread working upon a screw fixed solidly to the plate 25). 100

105 The arrangement which permits of doubling the speed of the traveller is as follows, Figure 3:-

The traveller 3 instead of carrying directly the punch 15 carries a pulley 27 upon which are passed in a contrary sense two cords 28 and 29 wound in an inverse sense and represented the one in dotted lines and the other by a line of crosses. These cords are attached to a framing surmounting the plate *c* at two opposed points 30 and 31, and they pass around pulleys 32 and 33 on the frame and are attached at 34, 35 to the punch carrier 36 which is guided by any suitable means, for example by two wires 37. The punch carrier carries the punch 15. It will be apparent that the speed of the punch carrier 36 is at any instant in a sense inverse to that of the traveller 3, but double that of the traveller. 110 115 120

125 To operate the apparatus, the operator introduces the slip holder containing the slip into the upper opening 20 of the apparatus. The slip holder fits accurately into the slip carrier *g*. The operator then operates the release *k* and so frees the lever *j* keyed upon the 130

shaft of the slip carrier. The latter then descends under its own weight and the punch 15 pierces a hole very neatly in the slip thereby making an indelible mark.

5 To recover the slip, the operator raises the lever *j* which becomes locked again and he then passes his fingers into the openings 40 and withdraws the slip.

In order to insure the accurate placing of 10 the slips in the slip holder which is essential for securing a correct marking the impression block has two circles 41 which are impressed upon the slip and are consequently situated in an invariable manner in relation 15 to the divisions of the slip.

The diameter and the position of the circles 41 are calculated in such a manner that the perforations 12 of a diameter slightly smaller should be found entirely within the interior 20 of the circles 41.

A spring seen to the left hand of the axis *h* in Figure 1 may be provided for throwing down the slip carrier when the lever *j* is released. Also, a regulator for this spring may 25 be provided.

I claim:

1. A card holder for a recorder of the type described comprising a pair of hingedly connected card guides and card centering means 30 carried by one of said guides engaging the other of said guides when said guides are moved to closed position.

2. A card holder for a recorder of the type described comprising a pair of hingedly 35 connected card guides, a plurality of card centering pins on one of said guides and a plurality of apertures formed in the other of said guides for receiving said pins when said guides are moved to closed position.

40 3. In a recorder of the type described having a casing and a card receiving slot in said casing, a reversible card-holder for insertion in said slot and means at each extremity of said slot cooperating with said card holder for determining the position in which said card holder may be inserted in said slot.

45 4. In a recorder of the type described having a casing and a card receiving slot in said casing, a reversible card holder for insertion in said slot and a hinged member at each end of said slot and means on one end of said card carrier adapted to cooperate with either of said hinged members for determining the position in which said card holder may be inserted in said slot.

50 5. In a recorder of the type described having a casing and a card receiving slot in said casing, a reversible card holder for insertion in said slot, a hinged member at each extremity of said slot, a guideway formed in each of said hinged members and a corresponding flange formed on one end of said card holder for determining the position in which said card holder may be inserted in said slot.

55 6. In a recorder of the type described hav-

ing a casing and a card receiving slot in said casing, a reversible card holder for insertion in said slot, means at each extremity of said slot cooperating with said card holder for determining the position in which said card holder may be inserted in said slot and a plurality of transversely disposed guide flanges on said card carrier.

7. In a recorder of the type described having a casing and a card receiving slot in said casing, a reversible card holder for insertion in said slot, a plurality of transversely extending guide flanges on said card-holder, a longitudinally extending guide flange at one extremity of said card-holder and a hinged member at each extremity of said slot each adapted to engage said longitudinally extending flange when said card-holder is inserted in said slot for the purpose disclosed.

8. A time recorder comprising in combination, a slidably mounted recording element, a pivotally mounted frame stationary with respect thereto, a reversible card-holder detachably mounted in said frame, time controlled means for displacing said recording element along one side of said card holder and back on the opposite side of said card holder when said holder is reversed and means for causing said frame to swing into operative relation to said recording element for the purpose disclosed.

9. A time recorder comprising in combination, a slidably mounted recording element, a pivotally mounted frame stationary with respect thereto, a reversible card-holder detachably mounted in said frame, a time-controlled means for displacing said recording element along one side of said card-holder and back on the opposite side of said card holder when said holder is reversed, means for causing said frame to swing into operative relation to said recording element, and means for determining the position in which said card holder may be inserted in said frame for the purpose disclosed.
